UNITED STATES PATENT OFFICE

111,057

DESIGN FOR A CUFF LINK

Edward L. Anderson, Attleboro, Mass., assignor to Ripley and Gowen Company, Incorporated, Attleboro, Mass.

Application October 28, 1937, Serial No. 72,486

Term of patent 3½ years

To all whom it may concern:

Be it known that I, Edward L. Anderson, a citizen of the United States, residing at Attleboro, in the county of Bristol and State of Massachusetts, have invented a new, original, and ornamental Design for a Cuff Link, of which the following is a specification, reference being had to the accompanying drawing, forming a part thereof.

The figure is a perspective view of a cuff link showing my new design.

The dominant features of my design reside in the grooved U-shaped yoke in combination with the links of the configuration shown.

I claim:

The ornamental design for a cuff link, as shown and described.

EDWARD L. ANDERSON.
